(57) **CLAIM**

The ornamental design for an electronic control unit, as shown and described.

DESCRIPTION

FIG. 1 is a front elevational view of an ornamental design for an electronic control unit;

FIG. 2 is a rear elevational view of the electronic control unit of FIG. 1;

FIG. 3 is a left side elevational view of the electronic control unit of FIG. 1;

FIG. 4 is a right side elevational view of the electronic control unit of FIG. 1;

FIG. 5 is a top plan view of the electronic control unit of FIG. 1;

FIG. 6 is a bottom plan view of the electronic control unit of FIG. 1;

FIG. 7 is a perspective view of a front, top, and right side of the electronic control unit of FIG. 1; and,

FIG. 8 is a perspective view of a rear, bottom, and right side of the electronic control unit of FIG. 1.

The broken lines in the drawings illustrate portions of the electronic control unit that form no part of the claimed design.

1 Claim, 5 Drawing Sheets
